GOLF TEE

James E. Rickard, Hollywood, Calif.

Application May 1, 1948, Serial No. 24,609

6 Claims. (Cl. 273—33)

1

This invention relates generally to appurtenances for playing the game of golf, and has to do more particularly with golf tees.

One of the objects of the invention is to provide a golf tee which will be exceptionally strong and durable and will be unusually satisfactory for the purpose of teeing up a golf ball on the green so that the ball may be driven in the usual fashion.

Another object of the invention is to provide a tee which may be easily inserted into the earth by reason of its being adequately slender and pointed at its lower end and will at the same time be formed from material sufficiently flexible to yield without rupture when struck with a golf club, the upstanding supporting portion being, however, sufficiently resistant to lateral bending movement to support the ball.

Heretofore, it has been a common practice to employ wooden golf tees which are easily shattered when struck with a golf club and therefore require a considerable quantity of them to be carried by the player. Attempts have been made to provide more durable golf tees but they have always been too bulky, or too short, or not sufficiently yielding when struck by a club, or have been produced from an excessive number of comparatively useless parts.

A more general object of the present invention is to provide a golf tee which overcomes all of the mentioned objectionable factors.

Another object of the invention is to produce a golf tee with a very tough, slender, sufficiently yielding rubber shank whose lower end is encased and firmly bound in a socket disposed in the upper end of a pointed metal spike tapered on a slight enough angle so that it may be easily inserted into the earth of the golf course. It is also an object of the invention to produce such a golf tee wherein the spike is of adequate length to maintain the tee in upright position, the metal portion being disposed below the level of the ground or at the ground level as its uppermost extremity, another object being to employ a sufficiently strong, upstanding, resilient stem that such stem may be formed with a length adequate to elevate the ball properly above the green or other portion of the golf course.

Another object is to provide a golf tee having a metal spike to be inserted into the earth and a ball supporting shank of material sufficiently tough that it will not break when hit by a golf club and will not tear away from the socket in which its lower portion is clamped to the spike. It is, consequently, another object to provide a golf tee which will not rupture and therefore will not leave metal parts or other portions which will interfere with lawnmowers by which the greens are clipped.

Other objects of the invention will become ap-

parent to those skilled in the art upon reference to the following specification and the accompanying drawing wherein one embodiment of the invention is disclosed for the purpose of illustration.

In this drawing:

Fig. 1 is an exploded view in vertical section showing the two parts of the golf tee of this invention prior to assembly;

Fig. 2 is a vertical section similar to that of Fig. 1, but showing the parts of the golf tee in assembled relationship ready for use;

Fig. 3 is an elevational view of the assembled golf tee in operative position, a golf ball being supported, as indicated by broken lines, in a normal playing position.

As illustrated in the drawing, the golf tee, according to this improvement, comprises an upstanding rubber shank 10, the lower end of which is securely anchored in the upper portion of a pointed or gradually tapered metal spike 12. The spike 12 is initially formed with a socket 14 which is semispherical at the bottom and is provided thereabove with an upright cylindrical wall portion 15. The socket 14 is adapted to receive a spherical lower end 16 of the rubber shank 10, the spherical lower end 16 being formed on substantially the same radius as the semi-spherical socket 14. The spherical end 16, having been thrust into the socket 14, the upper wall portion 15 is compressed above the spherical end 16 of the shank 10 to form a corresponding wall portion 15a of restricted diameter; that is, the external diameter of the restricted wall portion 15a is considerably less than the external diameter of the spherical end 16 of the shank 10. This results in an annular restriction 18 between the socket portion 14 and the lower end of the restricted wall portion 15a as viewed in Fig. 2 and in Fig. 3, so that the spherical end 16 is so positively clamped that it cannot be withdrawn through the restricted wall portion 15a.

The upper end of the shank 10 is provided with a somewhat enlarged head 20 which may flare out from the body of the shank 10, as illustrated, and is provided on top with a concavity 22 which constitutes a seat for the golf ball. In view of the slenderness of the shank 10, the head 20, which is circular in plan view, is expanded to a diameter about twice the diameter of the shank 10 which is similarly circular in cross section. The cup or concavity 22 is thus of adequate dimension to support the golf ball as indicated in Fig. 3.

In using the tee of this invention, the gently tapered spike 12 is forced into the earth, this being easily accomplished by grasping the top of the restricted wall portion 15a and pressing the device into place with the fingers. In the latter portion of the operation, the fingers may, if nec-

essary, also grasp the bottom of the shank 10, the forcing being continued until the top edge of the restricted wall portion 15a is approximately flush with the earth. In the form illustrated, the socket portion 14 constitutes a bulge of greater external diameter than the external diameter of the restricted wall portion 15a. As a consequence, there is a tendency for the earth to expand back over the top of the bulge and thereby somewhat facilitate the retention of the spike 12 in position in the ground. Proper placing of the spike 12 serves to dispose the shank 10 vertically upward so that the seat provided by the concavity 22 is directed uniformly upward for proper reception of the golf ball which is now in the relative position seen in Fig. 3. As the player drives with his golf club, his stroke may, for example, follow the arrow 25 seen at the right of Fig. 3, the purpose being to come in under the ball. When the club strikes the head 20 on the upper portion of the shank 10, the shank 10 flexes to the left somewhat as indicated by the dotted line position. The rubber of which the shank 10 and the head 20 are formed being extremely tough, the blow results merely in such flexing, there being no rupture whatever of the shank 10, either in its main portion or at its zone of contact with the upper edge of the restricted wall portion 15a. If desired, the inner portion of such edge may be slightly rounded for the purpose of avoiding any tendency which such upper inner edge position might have to cut into the outer wall of the shank 10.

When the ball has been driven, the player grasps the shank 10 and pulls the spike 12 from the earth. This is easily accomplished, and since the spherical lower end 16 of the shank 10 is positively and permanently bound in the socket 14 by reason of the configuration indicated, it is impossible for the spherical end 16 to be pulled from its socket. As a consequence, the golf tee may be used over and over, and it may be used a very great number of times before gradual wear will reduce it to a state of unfitness. Should it be that one of these golf tees is used for a time beyond its normal life so that the shank eventually breaks, it will be most apt to break off at the top of the spike 12 where it engages the upper edge of the constricted wall portion 15a. In this event, the metal spike 12 will remain in the earth below the level of operation of a lawnmower. As a consequence, there will be no damage to lawnmowers, nor will the green be cluttered up with metal pieces.

The rubber employed in producing the shank 10 is a very tough rubber having sufficient resilience to yield readily when struck by a golf club and having at the same time a sufficient hardness to remain erect when supporting the golf ball, or, in other words, having sufficient resistance to lateral bending when in a vertical position to support a golf ball resting in the concavity 22. Rubber very similar to conventional tread stock currently employed in automobile and truck tires is appropriate for the purpose. Such a rubber is effective for a shank having a diameter of from $\frac{3}{16}$ to $\frac{1}{4}$ inch and a total length from about $1\frac{1}{4}$ inches to about $1\frac{1}{2}$ inches, the exposed flexing portion of the shank having a length of about $\frac{5}{8}$ inch to about $\frac{7}{8}$ inch. The head 20 then has a diameter from about $\frac{3}{8}$ inch to about $\frac{1}{2}$ inch, and the spherical lower end 16 of the shank 10 has a diameter of approximately

$\frac{5}{16}$ inch or adequate to insure permanent retention thereof within the socket 14 as constricted to the closed or clamping position shown in Figs. 2 and 3. Ordinarily, the head 20 needs to be from $\frac{1}{8}$ inch to $\frac{1}{4}$ inch in depth at the flange portion to insure good support for the golf ball. Similarly, the restricted wall portion 15a of the spike 12 needs to be from about $\frac{1}{8}$ inch to about $\frac{1}{4}$ inch in height to insure desirable anchorage for the lower end of the shank 10. The spike 12 may vary from an over-all length of perhaps a little over 1 inch to as little as about $\frac{3}{4}$ inch as deemed desirable, the greater length probably being preferable if greater ease of insertion is desired.

15 It is, however, intended to protect all such variations of the generic invention as fall within the scope of the claims.

I claim as my invention:

1. A golf tee comprising: a rigid spike having 20 its lower end tapered and adapted to be forced into the earth; a rigid upwardly opening clamping socket carried by the upper end of said spike; an upstanding flexible shank formed of flexible material and having an enlarged lower end projecting into and fitting said socket and fixedly clamped therein against dislodgment from said socket and against movement in said socket; and a golf ball supporting cup fixedly carried by the upper end of said shank.

20 2. A golf tee as in claim 1 wherein said shank and supporting cup are formed from tough rubber offering bending resistance adequate to support a golf ball.

3. A golf tee comprising: a rigid spike having 35 a lower end pointed for forcing into the earth; an upwardly opening, integral ball socket on the upper end of said spike, the upper portions of said socket constituting overlying portions; a yieldable shank of flexible material having at its 40 lower end an integral ball fixedly gripped in said socket against movement therein and held therein by said overlying portions against dislodgment; and a golf ball carrying cup fixedly provided upon the upper end of said shank.

4. A golf tee as in claim 3 wherein the internal 45 diameter of said socket is greater than the diameter of said shank.

5. A golf tee as in claim 4 wherein said shank and carrying cup are of tough rubber adapted to yield without rupture to the blow of a golf club and possessing bending resistance when in upright position sufficient to support said golf ball.

6. A golf tee as in claim 3 wherein said shank and carrying cup are of tough rubber adapted to yield without rupture to the blow of a golf club and possessing bending resistance when in upright position sufficient to support said golf ball.

JAMES E. RICKARD.
